UNITED STATES PATENT OFFICE.

COURTNEY H. WEST, OF ST. LOUIS, MISSOURI, ASSIGNOR TO THE MOFFITT-WEST DRUG COMPANY, OF SAME PLACE

DESIGN FOR A PACKAGE-CASE.

SPECIFICATION forming part of Design No. 24,148, dated March 26, 1895.

Application filed November 22, 1894. Serial No. 529,656. Term of patent 14 years.

To all whom it may concern:

Be it known that I, COURTNEY H. WEST, a citizen of the United States, residing at the city of St. Louis, State of Missouri, have invented a certain new and original Design for Package-Cases, of which the following is a full, clear, and exact description, reference being had to the accompanying drawing, wherein the figure represents my new and original package-case.

This design relates to a new and original surface ornamentation, which is printed, stamped, or otherwise placed upon the side or sides of package cases, said ornamentation being composed of a number of scrolls arranged as shown in the drawing. These scrolls form substantially a frame or border, the top of which is elevated at its middle, forming an apex, while the vertical portions of the frame are formed by arranging the scrolls in sub-

stantially the same vertical plane. The bottom scrolls are disposed horizontally, and meet the vertical scrolls with reflex curves. These scrolls, arranged as above, are represented on a plain background, and within the frame so formed, may be placed printed matter.

The package case to which the design is applied, has a rectangular outline.

What I claim is—

The design for package cases, substantially as herein shown and described.

In testimony whereof I hereunto affix my signature, in presence of two witnesses, this 16th day of November, 1894.

COURTNEY H. WEST.
